(57) **CLAIM**

The ornamental design for a vehicle diagnostic tablet, as shown and described.

DESCRIPTION

FIG. 1 is a front upper perspective view the vehicle diagnostic tablet showing our new design;

FIG. 2 is a rear upper perspective view thereof;

FIG. 3 is a top plan view thereof;

FIG. 4 is a front elevational view thereof;

FIG. 5 is a rear elevational view thereof;

FIG. 6 is a bottom plan view thereof;

FIG. 7 is a right-side elevational view thereof; and,

FIG. 8 is a left-side elevational view thereof.

The evenly-dashed broken lines shown in the drawings illustrate features of the vehicle diagnostic tablet that form no part of the claimed design. The dash-dot-dot broken line showing of the cable in FIGS. 1 and 2 illustrate environment and form no part of the claimed design.

1 Claim, 5 Drawing Sheets
